UNITED STATES PATENT OFFICE.

ARTHUR C. WALKER, OF ROANOKE, VIRGINIA.

HAND STAMP.

Application filed August 26, 1926. Serial No. 131,729.

This invention relates to improvements in hand stamps and has as one of its objects to provide a hand stamp embodying a comparatively large number of bands bearing the letters of the alphabet, the digit numerals, and punctuation marks, and capable of adjustment so as to provide for the composition of one or several words or numbers, or combination of words and numbers.

Another object of the invention is to provide a hand stamp of the type referred to, so constructed that in a minimum space, a number of type bands of maximum length are arranged in connection with means for adjusting the said bands.

Another object of the invention is to provide a hand stamp of the type referred to, embodying novel means for suitably tensioning the type bands so as to maintain the same in the positions to which they are adjusted and likewise to insure of proper frictional contact of the bands with the rotatable elements over which they are trained.

Another object of the invention is to so construct the hand stamp that it may be laid upon any surface without likelihood of the type bands coming in contact with the surface to mar the same with ink.

Another object of the invention is to provide a hand stamp in which the component parts are extremely simple in construction and capable of being readily assembled and without the employment of extraneous fastening means for holding the parts in their proper relative positions.

Another object of the invention is to provide novel means for maintaining the type bands in parallel relation and properly spaced at their portions which are to be active.

In the accompanying drawings:

Figure 1 is a perspective view of the hand stamp embodying the invention.

Figure 2 is a view partly in rear elevation and partly in section, illustrating the stamp.

Figure 3 is a side elevation of the stamp.

Figure 4 is a vertical transverse sectional view taken substantially on the line 4-4 of Figure 2.

Figure 5 is a detail transverse sectional view through the type bar of the stamp.

Figure 6 is a longitudinal sectional view through a portion of the said type bar.

The frame or casing of the stamp is indicated in general by the numeral 1 and the same is preferably stamped from a single

integral sheet of metal. The said casing comprises a top 2, front and rear walls 3, and end walls 4, the end walls 4 being integrally joined at their upper ends, as at 5, to the ends of the top 2 and extending downwardly at right angles from the plane of the top, the marginal portions of the front and rear walls 3 fitting snugly against the front and rear edges of the said end walls 4. It will be observed by reference to Figures 1 and 3 of the drawings, that the end walls 4 are of gradually decreasing width in the direction of their lower ends and that consequently the front and rear walls of the casing are located in downwardly converging planes. For a purpose to be presently explained, the lower portions of the walls 3 are formed to curve inwardly toward each other, as indicated by the numeral 6, and these portions of the said walls 3 engage between the lower portions of the end walls 4, as clearly shown in Figures 1, 2 and 4 of the drawings. A hand knob 7 is secured in any suitable manner to the top 2 of the casing, midway between the ends thereof.

The stamp includes in its construction a plurality of type bands 8 which are preferably of rubber and endless, and each of which bears upon one side raised characters 9 which are preferably the letters of the alphabet, the digit numerals, and punctuation marks, and between the character bearing portions of the bands the bands are formed with notches 10 so that they are somewhat thin at these points, and likewise, in this manner, the characters are suitably relatively spaced.

The end walls 4 of the casing are formed each with a pair of openings 11 located near the upper corners of the said walls, and, below these openings, each with an opening 12. Spindles 13 are fitted at their ends in the openings 11 and one end of each spindle is circumferentially grooved, as indicated by the numeral 14, the groove being of a width equal substantially to the thickness of the end wall of the casing and the spindles are assembled by fitting their ends in the openings 11 with the grooves in the ends of the spindles accommodating the lower portions of the walls of the openings into which these grooved ends are fitted. In a like manner, a spindle 15 is fitted at its ends in the openings 12 and is provided at one end with a circumferential groove 16

engaging the upper side of the wall of the opening in which the said end of the spindle is seated. The grooved ends of the spindles are held in engagement with the walls 5 of the openings 11 and 12 by reason of the tensioning of the character bands as will presently be made clear, and the openings 11 which accommodate the grooved ends of the spindles 13 are located a distance higher 10 than the other openings 11 equal to the depth of the grooves in the spindle ends, and, in a like manner, the opening 12 which accommodates the grooved end of the spindle 15 is located lower than the other opening 15 12 a distance equal to the depth of the groove in the said spindle end, so that all of the spindles are parallel. The numeral 17 indicates a series of rollers freely rotatably mounted upon each of the spindles 20 13 and about which the type bands 8 are trained in the manner most clearly shown in Figure 4 of the drawings. It will be understood, of course, that each band is trained about a respective pair of the rollers 25 17, and the rollers may be made of any material found suitable for the purpose. From the adjacent sides of the rollers 17, the type bands 8 are led downwardly and each about a respective one of a series of friction rollers 30 18 which are freely rotatably mounted upon the spindle 15, each roller 18 being provided at one end with a thin, circular, disc-like head 19, and the opposite peripheral portions of these heads being arranged to project through slots 20 which are formed in the front and rear walls 3 of the casing above the concave portions 6 of the said walls. The peripheries of the heads are, 35 therefore, presented where they may be conveniently engaged to impart rotary motion to the respective friction rollers 18 and thus effect adjustment of the corresponding type bands 8.

From the outer sides of the rollers 17, the 45 type bands are led downwardly and beneath a type bar which is indicated by the numeral 21. This type bar is formed from a single integral sheet metal blank and comprises a channeled body including a bottom member 50 22 and front and rear upstanding flanges 23, the blank being formed with more or less gradual bends between the bottom member 22 and the flanges 23 so that the type bands 8 may pass about the under side of the type bar without engaging any sharp edges. The 55 ends of the bottom member 22 of the type bar are extended beyond the ends of the flanges 23 and are engaged in notches 24 formed in the lower ends of the end walls 60 4 of the casing of the stamp and these projecting end portions are bent up, as at 25, to engage against the outer sides of the said end walls at their said lower ends, the walls being, in this manner, restrained against 65 outward displacement. It will be observed

that the stretches of the type bands which extend downwardly from the outer sides of the rollers 17, pass over the inner or opposing sides of the concave portions 6 so that these stretches of the bands are flexed 70 and the bands are somewhat tensioned, the said stretches of the bands passing beneath the type bar. Inasmuch as the bands are tensioned, the grooved ends of the spindles 13 and 15 will be properly engaged in the 75 respective openings 11 and 12 and maintained in such engagement so that no extraneous fastening means need be provided to hold these spindles against longitudinal displacement. Likewise, in view of the fact 80 that the bands are tensioned, no means need be employed other than the projecting ends of the member 22 of the type bar to prevent displacement of said bar. In order that the bands may be held against lateral 85 displacement where they pass beneath the type bar and these portions of the bands likewise properly uniformly relatively spaced, the bottom member 22 of the type bar is preferably stamped or otherwise acted 90 upon to provide a series of spaced spacing ribs 26 which are shallow and project from the under side of the said bottom member 22 and extend between the longitudinal edges thereof or for a portion of the width 95 of the said member of the bar, as may be desired.

From the foregoing description of the invention it will be seen that the hand stamp embodying the invention is extremely simple 100 in construction and consists of parts which may be readily assembled. It will also be evident that due to the provision of the rollers 17 and the location of these rollers with respect to the friction rollers 18, type bands 105 of maximum length may be arranged within a very small space. It will also be observed that the portion of the band which passes about each roller 18 has its character-bearing face or side in contact with the said roller and due to the irregular character of 110 this side of the band because of the configuration of the raised characters thereon, the said portions of the band will more firmly grip the peripheries of the rollers. It will likewise be evident that due to the fact that the type bands are thinner at the relatively 115 adjacent ends of the raised character portions of the bands, and the character portions are of a length equal substantially to the width of the bottom member 22 of the type bar, there will be no tendency for the bands to shift after they have once been adjusted to bring a selected one of the character portions to position beneath the said bar. It will also be evident that the inwardly curved wall portions 6, which have 120 their convex sides smooth and presented inwardly for engagement by the type bands 8, constitute an extremely simple and yet high- 125 130

ly efficient tensioning means for the said bands.

Having thus described the invention, what I claim is:

- 5 1. A hand stamp comprising a casing having front, rear, and end walls, a type bar extending between the lower portions of the end walls, spindles extending between the upper portions of the end walls, rollers rotatably mounted upon the spindles, a spindle extending between the end walls below and in a plane between the first mentioned spindles, friction rollers rotatably mounted upon the last mentioned spindle, a head fixed 10 with relation to each of the said friction rollers, the front and rear walls of the casing having slots, the heads having portions of their peripheries projecting through the slots, and type bands trained over corresponding ones of the first mentioned rollers and beneath the corresponding friction rollers and beneath the type bar, the said front and rear walls of the casing having inwardly curved portions engaging the stretches of 15 20
2. A hand stamp comprising a casing having front, rear, and end walls, a type bar extending between the lower ends of the end walls, rollers mounted within the upper portion of the casing, rollers mounted within the casing beneath the first mentioned rollers and above the type bar, manually operable means associated with each of the last mentioned rollers whereby the same may be rotated, and type bands trained about corresponding ones of the said first and second mentioned rollers and beneath the said type bar, the front and rear walls of the said casing having inwardly curved portions the convex sides of which engage the stretches of the type bands above the type bar to tension said bands. 25 30 35 40 45

In testimony whereof I affix my signature.

ARTHUR C. WALKER. [L.S.]
